UNITED STATES PATENT OFFICE.

DANIEL B. MINOR, OF ST. PAUL, MINNESOTA, ASSIGNOR TO LESLIE S. HACKNEY, OF ST. PAUL, MINNESOTA.

FAN.

1,014,321.

Specification of Letters Patent.

Patented Jan. 9, 1912.

Application filed December 3, 1910. Serial No. 595,511.

To all whom it may concern:

Be it known that I, DANIEL B. MINOR, of St. Paul, Ramsey county, Minnesota, have invented certain new and useful Improvements in Fans, of which the following is a specification.

My invention relates to rotary fans of the blast or suction type and the primary object of the invention is to eliminate the 10 whirring or buzzing sound caused by the contact of the air with the fan blades and incidental to the operation of an ordinary fan.

A further object is to provide a fan which 15 will be practically noiseless and adapted for use in the living rooms of the house or in offices, stores, and other places where an ordinary fan, on account of its noise, could not be used.

20 The invention consists generally in providing one or more deflecting rings between the fan blades and the air intake.

In the accompanying drawings forming part of this specification, Figure 1 is a perspective view illustrating my apparatus 25 ready for use, Fig. 2 is a detail sectional view through the fan casing and fan, Fig. 3 is a similar view taken on a section line at right angles substantially to the section line 30 of Fig. 2, Fig. 4 is a detail sectional view showing the manner of mounting the deflecting rings in the fan casing.

In the drawing, (Fig. 1), I have shown two fan casings, 2 and 3, one for the intake 35 and the other for the exhaust, with the fans therefor mounted on the same shaft and driven preferably by a motor 4 interposed between the fan casings. These casings have central openings 5, one forming a fresh air 40 intake and the other an exhaust and said casings have trunks 6 and 7 communicating with suitable air ducts, one trunk directing the fresh air from one fan to the room to be ventilated and the other trunk directing 45 the foul air into the casing to be discharged through its exhaust opening. I thus arrange a fresh air and exhaust fan on the same shaft and thereby effect a considerable economy in space over what is required 50 when the fans and casings therefor are separately or independently arranged. I have shown the interior of one casing and this will sufficiently illustrate the invention, as the construction of the other fan is substantially the same.

8 represents a fan having radial blades 9 arranged at intervals around the periphery of the fan.

10 is a spider having a hub 11 that is secured on a shaft 12 by suitable means, said spider and shaft being concentric with the intake opening of the casing. I have found that where the air is drawn in this central opening and strikes the blades obliquely, that a whirring or buzzing sound will result, which causes the operation of the fan to be exceedingly annoying if located in a living room, sleeping room or office. The fan blades I have shown are of ordinary construction, corresponding to a great many 70 fans in general use. To obviate this noise resulting from the revolution of the fan, I provide rings 13 encircled by the fan blades and at right angles substantially to the plane of said blades and mounted on rods 75 14 having sleeves or thimbles 15. There may be any suitable number of these rings, but I have shown three herein. A greater or less number may be used, however, if preferred. The openings in the rings 80 register with the inlet opening 5 and when the air enters this inlet opening it must pass between the rings before coming in contact with the blades and these rings compel the air currents to move outwardly toward 85 the blades in a straight line or along the radial lines of the fan. The result is that the air currents do not impinge upon the edges of the blades obliquely but pass between them, following the lanes between the 90 rings and contacting with the blades squarely and do not produce the humming or whirring sound usually incident to the operation of a rotary fan. The efficiency of this device I have proven by the use of the apparatus embodying the invention in full size. I prefer to make these rings of sheet metal of suitable gage, but any other material may be used, if preferred, and I may modify the construction of the fan and 95 casing in various ways and still be within the scope of my invention. I have also found in the operation of an ordinary fan or blower that the currents of air striking the sharp angle in the wall of the casing at the exit will produce a sharp, whistling sound similar to a siren whistle, this sound being more marked the nearer the fan blades are to the angle of the wall. To obviate this I arrange a plate 16 within the 100 105 110

casing 2 extending from the angle 17 in the wall to a point within the casing forming the chord of the arc which includes the wall of the casing between the ends of the plate. 5 This plate is preferably arranged close to the fan blades, as indicated in Fig. 2, so that the air currents, instead of striking the sharp angle 17 and producing a whistling sound, will be drawn into the narrow 10 space between the blades and the plate 16, with the result that the air currents will not strike the sharp corner as before and the pressure will be equalized substantially on each side of this corner and the disagreeable 15 whistling sound will be entirely eliminated.

I claim as my invention:

1. The combination, with a rotary fan having a central air intake, of a ring 20 encircled by said fan blades and lying in a plane at right angles substantially to the plane of said fan.

2. The combination, with a rotary fan having a casing provided with a central air 25 intake, of a plurality of rings encircled by the blades of said fan and lying in planes at right angles substantially to the planes of said blades.

3. A rotary fan having a casing and a 30 central air intake and a series of radial blades, a series of flat rings encircled by

said blades and spaced apart and having central openings corresponding substantially to the air intake opening, and said rings operating to direct the air currents 35 radially into the path of said blades.

4. The combination, with a rotary fan having a central air intake and blades or vanes of uniform width substantially from end to end and a ring disposed within the 40 space inclosed by said vanes or blades and lying in a plane at right angles substantially to the planes of said blades, for the purpose specified.

5. The combination, with a casing, of a 45 rotary fan therein consisting of side plates and vanes or blades located between the outer portions of said plates, said casing having a central air intake and a peripheral discharge, rods passing through said fan 50 plates from side to side and a series of rings mounted on said rods and inclosed by said fan blades, said rings operating to direct the air currents between said blades and in a direction parallel substantially with 55 the planes thereof.

In witness whereof, I have hereunto set my hand this 25th day of November 1910.

DANIEL B. MINOR.
